(57) **CLAIM**

The ornamental design for a tire, as shown and described.

DESCRIPTION

FIG. 1 is a perspective view of a first embodiment of a tire showing our new design;

FIG. 2 is a front view thereof, the rear view being a mirror image;

FIG. 3 is a left side view thereof, the right side view being a mirror image;

FIG. 4 is a top view thereof, the bottom view being a mirror image;

FIG. 5 is a cross-sectional view taken along line 5-5 shown in FIG. 2;

FIG. 6 is a perspective view of a second embodiment of a tire showing our new design;

FIG. 7 is a front view thereof, the rear view being a mirror image;

FIG. 8 is a left side view thereof, the right side view being a mirror image;

FIG. 9 is a top view thereof, the bottom view being a mirror image;

FIG. 10 is a cross-sectional view taken along line 10-10 shown in FIG. 7;

FIG. 11 is a perspective view of a third embodiment of a tire showing our new design;

FIG. 12 is a front view thereof, the rear view being a mirror image;

FIG. 13 is a left side view thereof, the right side view being a mirror image;

FIG. 14 is a top view thereof, the bottom view being a mirror image; and,

FIG. 15 is a cross-sectional view taken along line 15-15 shown in FIG. 12.

(Continued)

The broken lines in FIGS. 11-15 show portions of the tire which form no part of the claimed design.

1 Claim, 15 Drawing Sheets
